UNITED STATES PATENT OFFICE.

WALTER F. GAGE, OF SMITH, NEVADA.

QUILTING-FRAME.

1,380,202.

Specification of Letters Patent. Patented May 31, 1921.

Application filed May 6, 1919. Serial No. 295,041.

To all whom it may concern:

Be it known that I, WALTER F. GAGE, a citizen of the United States, residing at Smith, in the county of Lyon and State of 5 Nevada, have invented certain new and useful Improvements in Quilting-Frames, of which the following is a specification.

This invention has for its object to provide an improved frame embodying such 10 novel features of construction as will permit the dimensions of the frame to be varied to accommodate it for use in connection with quilts of different sizes.

Another object is the provision of a quilting frame having a binding along the corner edges of the supporting members to which the material of the quilt or other object may be pinned or otherwise secured.

With these and other objects in view as 20 will appear as the description proceeds the invention comprises the novel features of construction, accompanied by elements and arrangement of parts which will be more fully described in the following specification 25 and set forth with particularity in the claims appended hereto.

Figure 1 represents a plan view of the improved frame,

Fig. 2 represents a vertical sectional view 30 on the line 2—2 of Fig. 1, and,

Fig. 3 represents a perspective view of one of the leg attaching members of the frame detached.

Referring to the drawing in detail, where- 35 in similar reference numerals designate cor- responding parts throughout the several views the numerals 5 indicate a pair of companion side members which may be con- structed of wood or other suitable material 40 and are formed at corresponding intervals with transverse recesses 6 adapted to be re- ceived within the recess portions 7 of the end members 8 whereby the side and end members are interlocked in adjusted posi- 45 tion. As will be understood, the distance between the end members 8 may be varied, as desired, by engaging said members with the proper recesses 6 in the side members 5 and likewise the relative position of the 50 side members may be varied by engaging them in the proper recesses 7 in the end members 8.

A pair of substantially U-shaped com- 55 panion leg attaching plates 9 and 11 is se- cured to the underside and adjacent each end of the members 5 by rivets or suitable

fastening devices passed through registering apertures 13 formed on the facially abutting web portions of the plates and the terminals of the plates or attaching members are di- 60 rected angularly in spaced parallel relation as indicated at 10 and 12, the terminals be- ing spaced an adequate distance apart to accommodate the reduced terminals 15 of the inclined supporting legs 14 and the lat- 65 ter are detachably and pivotally supported in the attaching members by winged bolts 16.

The inner edges of the side and end mem- bers 5 and 8 are bound by a strip of fabric 17 secured in position by headed fasteners 70 18 and constituting adequate anchoring means for pins or other penetrating elements capable of securing the quilt or other object in position upon the frame.

In the foregoing it is evident that I have 75 provided a quilting frame, which, when not in use, may be disassembled and stored in a comparatively small space, owing to the compact manner in which the parts may be grouped subsequent to detachment. In 80 use, the legs 14 are secured in position by the screws 16 and the quilt or other work is secured in position by inserting pins through the edges of the material and through the fabric binding strips 17, proper adjustment 85 of the side and end members being had by engaging them in appropriate recesses in the respective members.

What I claim is:

1. A quilting frame including an adjust- 90 able frame structure, leg supporting mem- bers carried by the frame structure, said leg supporting members including substantially U-shaped plates having web portions of dif- 95 ferent lengths arranged one above the other and in facial abutment, said web portions being provided with registering openings, means passing through said openings and engaged in the frame structure for main- 100 taining the leg supporting members in posi- tion thereon, the angular extremities of the lower plate being arranged in spaced re- 105 lation to the angular extremities of the upper plate to provide spaces therebetween, in- clined legs having the upper terminals con- fined between the spaced angular extremi- 110 ties of the plates, and means to clamp said legs in position between said angular ex- tremities.

2. A quilting frame including an adjust- 110 able frame structure, leg supporting mem- bers carried by the frame structure, said leg

supporting members including substantially U-shaped plates having web portions of different lengths arranged one above the other in facial abutment and provided with 5 registering openings, means passing through said registering openings and engaging the frame structure to rigidly secure the leg supporting members in position, the angular extremities of the lower U-shaped plate 10 being disposed in spaced relation to the angular extremities of the upper plate, in-

clined legs received in the spaces between the extremities of the plates, a pivoting member extending through the spaced extremities of the plates and the leg for pivotally mounting the latter, and means to draw said angular extremities of the plates together to clamp the legs in adjusted position. 15

In testimony whereof, I affix my signature 20
hereto.

WALTER F. GAGE.
